UNITED STATES PATENT OFFICE

2,289,147

HIGH FREQUENCY RECEIVER

Richard F. Shea, Bridgeport, Conn., assignor to
 General Electric Company, a corporation of
 New York

Application August 22, 1940, Serial No. 353,665

9 Claims. (Cl. 250—20)

My invention relates to high frequency receivers and more particularly to receivers adapted, for example, to home radio reception employing both uncontrolled tuning means variable over a desired range, and fixed tuning means to tune the receiver to fixed frequencies in said range, the fixed frequencies being selected by switches, such as the push buttons of ordinary household receivers.

It has for one of its objects to effect certain economies in the construction of such receivers.

A further object of my invention is to provide means to avoid employment of fixed tuning means in the interstage circuits operating at the received frequency.

A further object of my invention is to provide means whereby when the receiver is adjusted for push button operation, the interstage tuned circuits are rendered ineffective, or removed from the circuit, and an untuned broad band pass network is utilized to furnish the desired interstage coupling.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which the single figure represents an embodiment of my invention.

Referring to the drawing I have illustrated therein a portion of a radio receiver comprising a radio frequency amplifier employing an electron discharge device 1, a local oscillator 2, and a converter 3 for converting the received oscillations and the oscillations produced by the local oscillator 2 to oscillations of fixed frequency for all received frequencies. The output of this converter, which is of constant frequency for all received frequencies, is supplied to a tuned circuit 4 tuned to this constant frequency which in a superheterodyne receiver is ordinarily known as the intermediate frequency. Those portions of the receiver subsequent to the circuit 4 are not shown in the drawing since their nature does not pertain to my present invention.

The control grid of the radio frequency amplifier 1 is connected through a coupling condenser 5, the movable contact 7 of a switch designated on the drawing as S, and a tuning condenser 8, to the cathode of the discharge device. Similarly, the control grid 9 of the converter 3 is connected through movable contact

10 of the switch S and tuning condenser 11 to the cathode of the discharge device 3. Likewise, the control grid 12 of the local oscillator is connected through the grid condenser 13 thereof, movable contact 14 of the switch S and tuning condenser 15 to the cathode of the discharge device 2. The tuning condensers 8, 11, 15 are arranged for unicontrol as indicated by the dotted lines shown on the drawing interconnecting these different condensers, and comprise the ordinary means for tuning respectively the input circuit of the amplifier, the coupling circuit between the amplifier and the converter, and the local oscillator thereby to select the desired stations which are to be received.

The switch S is the band change switch of the receiver and may be of the ordinary Yaxley wafer construction but for purposes of illustration is shown on the drawing as having a plurality of contacts such as the contacts 6, 7, 10, 14 already mentioned and others presently to be mentioned, all interconnected for unicontrol as indicated by the dotted lines to which the character S has been applied on the drawing.

This switch has four positions. In the position shown it connects the receiver for tuning by means of the uncontrolled variable condensers 8, 11, 15 over a range of frequencies which may be the broadcast band. This may be designated the B position of the switch. It may be moved to the left to either of two positions C and D in which it connects the receiver for tuning over either of two higher frequency bands by means of condenser 8, 11, 15, or it may be tuned to the right to position A in which it disconnects condensers 8, 11, 15 from the circuit of the receiver and substitutes in the place of condenser 8 a fixed condenser 17 plus the push button switching mechanism 18 shown at the top of the drawing. It also substitutes for condenser 15 the fixed condenser 15' shunted by an inductance 19 connected thereto through certain switches of the push button mechanism 18.

It also, in its A position, disconnects condenser 11 from the receiver circuit so that the inductive coupling circuit between amplifier 1 and converter 3 is untuned and rendered ineffective, and at the same time it disconnects a fixed by-pass condenser 20 from the receiver thereby to render effective between the amplifier 1 and the converter 3 a broad band resistance capacity coupling comprising elements 26, 30, 56 and 58, which will be more particularly mentioned hereinafter.

The circuits of the receiver in each position of

the switch S will now be described in detail. With the switch in the position B, which is that shown on the drawing, the input circuit to the amplifier 1 extends through the condenser 5, variable contact 6 of the switch S in its B position and loop antenna 21 to ground 22 and thence back to the cathode of amplifier 1. The loop antenna 21 is designed for operation in the broadcast band which extends from about 550 to 1700 kilocycles and is tuned by the variable condenser 8 and the trimmer condenser 23.

The anode circuit of the amplifier extends through the primary winding 24 of a transformer 25 and through resistance 26 to the source of high voltage operating potential for the receiver, the positive terminal of which is indicated by the line 27, and the negative terminal of which may be grounded. With the switch S in the position shown the secondary winding 28 of this transformer is connected by means of contacts 29 and 10 thereof across the variable condenser 11, these movable contacts 29, 10 being connected to the control grid of the converter 3. This control grid is connected through the winding 28 and a resistance 30 to the bus 31 which may be the automatic volume control bus of the receiver. This bus includes a resistance 32 and is connected to ground through a condenser 33 which elements may comprise an ordinary automatic volume control filter circuit. The secondary winding 28 of transformer 25 is tuned by means of condenser 11 and trimmer condenser 34.

At the same time the cathode of the local oscillator 2 is connected through movable contact 35 of the switch S to an intermediate point on the tuned circuit 36, one terminal of which is connected to ground and thence through condenser 37 to the anode of the discharge device 2, and the opposite terminal of which is connected through a series alignment condenser 38, movable contact 39 of the switch, and grid condenser 13 to the grid of the oscillator 2. This grid is connected to ground through the ordinary oscillator grid resistance 40. The tuned circuit 36 is tuned over the band of frequencies corresponding to the broadcast band of received frequencies by means of the condenser 15.

With the circuits as thus described the receiver is adapted for reception of the broadcast band of frequencies by means of the loop 21 and by variation of the tuning of the receiver by means of condensers 8, 11, 15.

The loop antenna 21 is provided with a tap connection 41 which is connected through an inductance 42 and contact 43 of the switch to an antenna 44 which may be the ordinary outdoor antenna for home reception which may be utilized in situations where the directivity of the loop 21 is not highly important.

Such a connection of an ordinary outdoor antenna and loop is shown and claimed in application Serial No. 238,417, filed November 2, 1938 by George W. Fyler entitled Radio receivers, now Patent No. 2,222,709, issued November 26, 1940, and which is assigned to the assignee of my present application. The antenna is connected to ground through a resistance 45 which coacts with the inductance 42 to aid in the suppression of image frequencies.

If the switch be moved to its C position, the input to the amplifier 1 is changed by substitution of loop 46 for loop 21, this loop being tuned by the condenser 8 and trimmer 47 for reception of a higher band of frequencies. An inter-

mediate point on the loop 46 is also connected through contact 43 of the switch to the antenna 44, but in this case no means for suppressing image frequencies is employed.

5 A second primary winding 47 of the interstage coupling transformer 25 is now connected in parallel with the primary winding 24 by means of contact 48 of the switch and secondary winding 28 is now removed from the grid circuit of the converter and in its place is substituted secondary winding 49, this winding being tuned by condenser 11 and trimmer 49'.

The oscillator circuit is now changed by contact 39 of the switch by substitution of oscillating circuit 50 for the oscillating circuit 36.

If switch S be moved to its D position, loop 51 is substituted in place of loop 46, this loop being tuned by means of condenser 8 and trimmer 52 over a still higher band of frequencies.

20 Primary winding 47 is now removed from the output circuit of the discharge device 2, leaving only primary winding 24. Secondary winding 53 is now inserted by means of contact 29 of the switch in the grid circuit of the converter, this secondary winding being tuned by condenser 11 and trimmer 53' over said higher frequency band. In the oscillator circuit the tuned circuit 54 is substituted for the tuned circuit 50.

In all positions B, C and D of switch S the coupling between the radio amplifier 1 and converter 3 is effected practically entirely by the transformer 25 and condenser 58. Resistance 26 may desirably be of about twenty-two hundred ohms and has connected in parallel with it the

35 series combination of coupling condenser 56 and by-pass condensers 20 and 20' and hence it has very small effect upon coupling between the circuits of the two discharge devices. Resistance 30 is shunted by the path comprising condenser

40 20 connected between its upper terminal and ground and condenser 33 connected between its lower terminal and ground, and thus has practically no effect on the coupling between the circuits. Condenser 56 is of about two or three

45 hundred micro-microfarads.

If the switch S be moved to the right, to the A position, the tuning condensers 8, 11, 15 are all removed from the circuit and the broadcast band loop 21 is restored to the circuit. The grid

50 circuit of the amplifier 1 is now tuned by means of a condenser 17 which is connected thereto through the various contacts of the push button assembly 18. Similarly, the tuned circuit 36 of

55 the oscillator is now restored to its circuit relation with discharge device 2 and has connected across it the inductance 19. This circuit extends from ground through the circuit 36, movable contact 39 of switch S, movable contact 14 of switch S, conductor 57, upper contacts of the lower armatures of push button assembly 18 and inductance 19 to ground, this circuit being tuned to a desired frequency by adjustment of inductance 19. Condenser 11 is removed from circuit by contact 10, and therefore, the transformer 25

60 65 is no longer tuned thereby. The by-pass condenser 20 is open circuited by contact 55 of the switch. In this way the transformer is rendered substantially ineffective as a coupling means between the amplifier and converter but resistances 26 and 30 are now effective as coupling resistors in a coupling network comprising these resistors and condensers 56 and 58, the latter of which is connected directly between the anode of amplifier 1 and the control grid of the converter.

70 75 These elements 26, 30, 56 and 58 may be propor-

tioned to act as a wide band coupling network which is effective to transmit any frequency in the broadcast band or which may be selected by the push button assembly.

The various stations which may now be selected are determined by the push buttons 60, 61, 62, 63, 64, 65 on the push button assembly. Push buttons 60 to 64 are each provided with two movable contacts or armatures, one of which is connected in the amplifier input circuit and the other in the oscillator circuit, and each armature has two positions, namely, the position shown in the drawing and a lower position in which it is retained by means of a latch member 66 having slots 67 therein through which the push button members extend. The latch 66 is biased by means of a spring 68 against the push button. Each push button member is also provided with a pawl 69 which cooperates with the slot 67 on the latch so that when the push button is operated downwardly the latch is moved to the right until the pawl has completely passed the latch. The latch then returns to its initial position latching the operated push button in its lower position. When the latch is thus operated, any other push button previously operated to its lower position, is released. Push button 65 is not provided with any contact armatures but operates when pressed to restore buttons 60 to 64 to the position shown in the drawing inserting condenser 17 and coil 19 in their respective circuits.

It will be understood that the mechanical details of this push button assembly just described are described solely by way of illustrating one form of push button assembly which may be used. Any of the forms now commonly in use may be employed.

When push button 60 is operated to its downward position, the input circuit of the receiver is tuned to a frequency determined by fixed condenser 70 and the local oscillator is tuned to a frequency determined by inductance 71. When push button 61 is operated, push button 60 is released and the input of the receiver is then tuned to a station determined by condenser 72 and the local oscillator is tuned to a frequency determined by inductance 73. The condensers 17, 70, 72, etc., may, if desired, be of any suitable type variable for purposes of initial adjustment and the inductances 19, 71, 73, etc., may be of the iron core type in which the core is variable for variation of the tuning of the oscillator over a desired range for purposes of initial adjustment.

It will be seen that by the use of my invention it is unnecessary to provide on the switch assembly 18 an additional set of movable contacts and associated tuning reactances controlled by the push buttons to effect the tuning of the interstage coupling circuit between amplifier 1 and converter 3, this complication being avoided by the simple use of the resistance capacity coupling circuit 26, 30, 56, 58, which is rendered effective by means of contact 55 of the switch. Thus, when the receiver is adjusted for push button tuning, wide band coupling is used in the interstage circuits and tuning thereof to the different stations preset by the push button assembly is avoided.

In addition, with switch S adjusted to either the B or C positions resistance 30 and condenser 20 serve as an additional filter in the automatic volume control circuit to the grid 9 of the converter. It aids in reducing audio frequency or intermediate frequency, feed back from the au-

tomatic volume control rectifier, now commonly employed in such receivers, through conductor 31 now resistance 30 to the grid 9 of the converter. When switch S is in the D position, for operation in the highest frequency band the lower terminal of resistance 30 is grounded and the automatic volume control circuit to grid 9 of the converter is interrupted by contact 80 of the switch. This is desirable because in the upper portion of the D frequency band voltage of the frequency of the oscillator appears in considerable quantity on the grid 9 producing rectification and unidirectional voltage on the filter resistors in the automatic volume control circuit which tends to bias the amplifier and converter to cut off. This is avoided by interrupting the circuit at the contact 80.

While I have shown a particular embodiment of my invention, it will, of course, be understood that I do not wish to be limited thereto since many modifications both in the circuit arrangement and in the instrumentalities employed may be made and I contemplate by the appended claims to cover any such modifications as fall within the true spirit and scope of my invention.

What I claim as new and desire to secure by Letters Patent of the United States is:

1. In combination, a pair of electron discharge amplifiers, coupling means between said amplifiers tunable over a range of frequencies, untuned means coupling said amplifiers over the same range of frequencies, and switching means for rendering said tunable coupling means and said untuned coupling means alternatively effective over said range of frequencies.

2. In combination, a pair of electron discharge amplifiers, one of said amplifiers having an output circuit, and the other of said amplifiers having an input circuit, a coupling between said circuits, a resistance in said output circuit, means to tune said coupling to a desired frequency, means to render said tuning means ineffective and means to supply potential variations on said resistance to said input circuit at all frequencies over a wide range.

3. In combination, a pair of electron discharge amplifiers, tunable coupling means between the output electrodes of one of said amplifiers and the input electrodes of the other amplifier, a circuit between said output electrodes including an element of said coupling means and a resistance, a shunt path around said resistance, means connected to said coupling means to tune said coupling means to any desired frequency in a wide band of frequencies, means to render said last means ineffective and to interrupt said shunt path, and means to supply the potential variations on said resistance to said input electrodes.

4. In combination, a pair of electron discharge amplifiers, coupling means between said amplifiers, means to supply operating potential to the anode of one of said amplifiers through a resistance and an element of said coupling means, means to supply bias potential to a grid of the other of said amplifiers through a resistance and an element of said coupling means, a shunt path between the cathodes of said discharge devices and the points between said resistances and said reactive coupling means for currents of the frequency at which said amplifier operates a capacitance between said anode and grid, means to tune said coupling means to said frequency, means to disable said tuning means and simultaneously to interrupt said shunt path, said

resistances and said capacitance being proportioned to operate as a resistance capacity coupling network between said amplifiers over a wide range of frequencies.

5. In combination, an electron discharge device having an anode circuit including the primary winding of a transformer and a resistance in series, a second electron discharge device having a grid circuit including a secondary winding of said transformer and a resistance in series, a capacitance between the anode of said first electron discharge device and the grid of said second electron discharge device, a low impedance path between the cathodes of said discharge devices and the points on said circuits between said windings and the respective resistances for frequencies at which said discharge devices operate, and means to interrupt said path, said resistances and said capacity being proportioned to act as a resistance-capacity coupling between said discharge devices when said path is interrupted.

6. In combination, an electron discharge device having an anode circuit including the primary winding of a transformer and a resistance in series, a second electron discharge device having a grid circuit including a secondary winding of said transformer and a resistance in series, a capacitance between the anode of said first electron discharge device and the grid of said second electron discharge device, a low impedance path between the cathodes of said discharge devices and the points on said circuits between said windings and the respective resistances for frequencies at which said discharge devices operate, a tuning reactance connected to said transformer to tune it to the frequency at which said discharge devices operate, and means to disconnect said tuning reactance from said transformer and to interrupt said low impedance path, said resistance and said capacity being proportioned to act as a resistance capacity coupling between said discharge devices when said path is interrupted.

7. In a radio receiver having means to tune said receiver to any frequency in a predetermined range, means to tune said receiver to any one of a plurality of fixed frequencies in said range, and switching means to render said last two

means alternatively operative, the combination of a tuned coupling network between two stages in said receiver, said first tuning means including means to tune said coupling network to select any frequency in said range, a normally ineffective broad band coupling network between said stages, and means responsive to operation of said switching means to render said fixed frequency tuning means effective, to render said tuned coupling network ineffective and to render said broad band coupling network effective.

8. The combination, in a radio receiver having a tunable coupling network between different electron discharge stages of said receiver, of means to tune said receiver over a band of frequencies, said means including means to tune said network over said band of frequencies, switching means arranged to tune said receiver to any one of a plurality of fixed frequencies in said band, means to render said tuning means and switching means alternatively effective, a capacitive interstage coupling network, and means responsive to operation of said last means to render said switching means effective, to render said tunable coupling network ineffective and to render said capacitive coupling network effective between said stages.

9. In a high frequency receiver having a received frequency amplifier, a local heterodyne oscillator, and a converter to combine the received oscillations amplified by said amplifier with the oscillations produced by said local oscillator to produce additional oscillations, a tuned coupling between said amplifier and converter, said amplifier, tuned coupling and local oscillator being tunable over respective ranges of frequencies such that said additional oscillations are of constant frequency for all received frequencies, the combination of an untuned coupling between said amplifier and converter, switching means to tune said amplifier and oscillator to any one of a plurality of fixed frequencies throughout their respective ranges, and means responsive to operation of said last means to render said tuned coupling ineffective and said untuned coupling effective between said amplifier and converter.

RICHARD F. SHEA.
